UNITED STATES PATENT OFFICE.

LEONARD R. STEEL, OF CLEVELAND, OHIO.

MILK-CAN.

1,053,236.

Specification of Letters Patent. Patented Feb. 18, 1913.

Application filed March 4, 1911. Serial No. 612,235.

To all whom it may concern:

Be it known that I, LEONARD R. STEEL, a citizen of the United States, residing at Cleveland, in the county of Cuyahoga and State of Ohio, have invented new and useful Improvements in Milk-Cans, of which the following is a specification.

This invention relates to milk or cream cans, the object of the invention being to provide an outer metal jacket and an inner glass vessel which are connected with each other so that the vessel can be readily removed when it is desired to clean or sterilize the same and the outer jacket.

Another object of the invention is to provide in the construction of the outer jacket means whereby the inner glass vessel will be substantially entirely out of contact with the walls of the outer jacket and spaced sufficiently therefrom to prevent breakage of the inner vessel in transit of the can.

Another object of the invention is to provide an efficient form of fastening device for connecting the separable portions of the outer jacket with each other.

In the drawings, forming a portion of this specification and in which like numerals of reference indicate similar parts in the several views, the figure is a vertical section through my improved can.

My improved can comprises an outer metal jacket which includes upper and lower separable sections 1 and 2. The lower section 2 is substantially of the same transverse diameter throughout, the said section being formed of metal and formed at its upper end with an inwardly extending offset portion 3. From the offset portion extends a vertical flange 4 to which is secured by means of rivets or suitable equivalent fastening devices 5 a shield 6. The shield extends horizontally with respect to the section 2 of the can and it entirely surrounds the upper end thereof, being provided with a peripheral vertical flange 7 which is spaced from the flange 4, as shown, and which preferably extends upwardly above the plane of the top of the section 2. The top section 1 is curved upwardly and inwardly from the top of the lower section 2 and it is formed to provide a contacting portion 8 for a purpose to be hereinafter explained. The top section is formed with a central opening 9 which is entirely surrounded by a vertical flange or collar 10 which is formed at the top of the section 1. This flange has

secured thereto by rivets or other suitable equivalent fastening devices 11 a vertically disposed collar 12, the same being extended upwardly a considerable distance beyond the flange or collar 10 so as to form a relatively broad exteriorly presented contacting surface for the flange 13 of the cover 14. The cover 14 is formed with an outwardly flared portion 15 having a peripheral bead 16 provided for the purpose of protecting the flange 13 against contacting with objects in transit of the can. The bottom section 2 is provided with a bottom member 17 which is horizontally disposed and which is formed with a peripheral depending flange 18 which interiorly embraces the lower walls of the section 2, as clearly shown in the drawing. The bottom walls of the section 2 are exteriorly embraced by a reinforcing band 19 or collar 19. A similar band or collar 20 contacts with the interior surface of the depending flange 18 of the bottom, and as illustrated, rivets or the like 21 are extended through the flanges 18, 19 and 20 and 80 through the bottom walls of the section 2.

The inner vessel or jar 22 is formed of glass, being provided on its bottom at its point of connection with the vertical walls 23 of the jar with a curved surface 24 to facilitate cleaning of the jar and to prevent the accumulation in the bottom thereof of any foreign matter. At the top, the jar is formed with a vertically disposed neck 25 which is exteriorly screw-threaded to receive a correspondingly threaded flange 26 of a cover 27. The cover 27 is preferably constructed of metal, and as illustrated, a paper cap 28 is located beneath the cover for the purpose of preventing the exposure of any metal part of the cover to the contents of the jar. The cover is provided with a suitable handle 29.

The transverse diameter of the section 2 exceeds the transverse diameter of the jar 100 22 so that when the jar is operatively placed in the outer jacket the walls thereof will be spaced from the walls of the jacket. With a view of holding these parts in proper spaced relation I provide the bottom 17 of 105 the lower section 2 with a vertically disposed spacing member 30. This member is provided with a horizontal flange 31 which is riveted or otherwise suitably secured to the bottom 17. In addition to the member 110 30 I provide upper spacing devices 32 which are secured in any suitable well known man-

ner to the lower section 2. Each member 32 is provided with an inwardly extending offset portion 33 which is adapted to bear against the jar 22 adjacent to the upper end 5 thereof. The bottom of the jar is entirely embraced by the member 30. The contact portion 8 of the top section 1 of the outer jacket operatively bears against the top portion 34 of the jar so as to insure against dis- 10 placement of the bottom of the jar from the member 30.

Plates 35 are secured to the underside of the shield 6. These plates are provided with vertically extending staple-like portions 36 15 which are adapted to be extended through slots 37 in the base flange 38 on the top section 1 of the outer jacket and to be presented for engagement with snap fastenings 39 which are supported by chains or suitable flexible elements 40 which are carried by the top section 1. When the snap fastenings are engaged with the said staple-like portions of the plates 35 the top section and the bottom section of the jacket are 25 surely connected with each other.

When pouring the contents of the inner jar the covers 14 and 27 are removed and to prevent the contents of the jar from coming in contact with any metal parts of 30 the can I preferably construct the neck of the jar so that it will be extended beyond the collar 12, as shown. The contents of the jar can then be poured directly into any receiving vessel without the contents coming 35 in contact with the collar 12 or with any metal parts of the structure.

Suitable handle attaching plates 41 are secured to the lower section of the jacket and they pivotally support such bails or 40 handles as the one shown at 42. When it is desired to sterilize the jar or to clean the outer jacket interiorly the upper section of the outer jacket is removed from the lower

section so as to expose the upper end of the jar and to permit of it being conveniently 45 grasped for entire removal vertically in the lower section of the jacket, as will be understood. The jar 22 is graduated vertically so as to indicate the exact quantity of milk contained. The flange 13 of the cover 14 50 is provided with a suitable staple or eye 43 which is located in such proximity with respect to a similar eye or staple 44 on the upper section 1 of the jacket so as to receive therewith a suitable seal, whereby the 55 cover can be securely held in its closed position. The section 2 of the jacket is corrugated or substantially fluted vertically so as to present rigidity to the section and to greatly reinforce the same. 60

I claim:

A can, including upper and lower sections, the lower section being provided with an inwardly offset upper portion and having a vertical annular flange extending from 65 said portion, a shield embracing the flange and bearing against the offset portion, means connecting the shield with the flange, the said upper section of the can being adapted to embrace the inner wall of the 70 shield and having a base flange lying in flat contact with the bottom of the shield, means extending through the bottom of the shield and through the base flange of the said upper section, and a fastening device carried 75 by the upper section and having detachable engagement with said means whereby to hold both sections of the can against retrograde rotation and against longitudinal displacement. 80

In testimony whereof I affix my signature in presence of two witnesses.

LEONARD R. STEEL.
